O. CARMICHAEL.

WAGON.

APPLICATION FILED SEPT. 28, 1917.

1,272,330.

Patented July 9, 1918.

By Whittenton, Hallard & Whittenton

Attorneys.

UNITED STATES PATENT OFFICE.

ORAL CARMICHAEL, OF TOLEDO, OHIO, ASSIGNOR TO GENDRON WHEEL COMPANY, OF TOLEDO, OHIO, A CORPORATION OF OHIO.

WAGON.

1,272,330.

Specification of Letters Patent.

Patented July 9, 1918.

Application filed September 28, 1917. Serial No. 193,673.

To all whom it may concern:

Be it known that I, ORAL CARMICHAEL, a citizen of the United States of America, residing at Toledo, in the county of Lucas and State of Ohio, have invented certain new and useful Improvements in Wagons, of which the following is a specification, reference being had therein to the accompanying drawings.

10 The invention relates to hand wagons and has for its object the obtaining of a simple construction, in which a portion of the bottom may be quickly adjusted to form a seat. The invention therefore comprises the novel 15 features of construction as hereinafter set forth.

In the drawings:

Figure 1 is a longitudinal section through the wagon showing different positions of adjustment respectively in full and dotted lines;

Fig. 2 is a bottom plan view showing the seat in lowered position;

Fig. 3 is a cross section.

25 A are the wagon sides, B the ends and C the bottom. This bottom is formed of immovable end sections, C' and C², and a removable intermediate section C³. The latter is of a width to move between the sides 30 A and is supported at its opposite ends by resting upon ledges D formed by cross cleats D' and D² on the bottom. E are parallel links, preferably formed of metal bars arranged upon opposite sides of the removable section C³, being pivotally connected thereto at one end and at their opposite ends pivotally connected to the immovable bottom. The pivotal connections are preferably formed by metallic angle bars F, and 40 the arrangement is such that when the bottom is raised the links will swing in parallelism and will carry the movable section upward and to the rear until its rear end abuts against the wagon end B. In this position 45 the links will be arranged obliquely so that the load resting upon the section C³ will hold it from forward and downward movement.

To facilitate the construction of the bottom the sections C' C² and C³ are all formed of the same width, which is slightly less than the space between the sides A, and edge bottom bars G and G' are arranged upon opposite sides of these sections. These 55 bars are secured to the sides A, and the cross

cleats D' and D² connect the sections C' and C² to said side bars so as to hold them rigidly in position. The top edges of the sides A are also preferably provided with finishing rails H and the ends B with finishing rails I.

50 The construction as described can be manufactured at low cost and will adapt the wagon for instantaneous adjustment from a seatless, full-bottom construction to one provided with a seat.

What I claim as my invention is:

1. A wagon, comprising sides, ends and a bottom formed of fixed and movable sections, parallel links connected to said movable section and arranged on opposite sides thereof, said links being positioned and proportioned to swing said movable section from the plane of the bottom to a plane adjacent to the top, with the rear edge in contact with the rear end of the wagon, said links being rearwardly inclined to the raised position of the movable section.

70 2. A wagon, comprising sides, ends and a bottom formed of fixed and movable sections, the movable section being intermediate fixed sections at opposite ends of the wagon, and parallel links arranged at opposite sides of the movable section and pivotally connected thereto, said links permitting 75 the swinging of said movable section from the plane of the bottom to a plane adjacent to the top and in the upper position of adjustment standing obliquely to the rear with the rear edge of the movable section abutting 80 against the rear end of the wagon.

85 3. A wagon, comprising sides, ends and bottom, the latter being formed of edge bars and a plurality of sections intermediate said edge bars of slightly lesser width than the space between the wagon sides, the intermediate one of said sections being movable and the end sections fixed, and parallel links for connecting said intermediate section to said edge bars adapted to permit the 90 swinging of said movable section from the plane of the bottom to a plane adjacent to the top, with its upper face flush with the upper edges of the sides and ends and its rear edge abutting against the end.

100 4. A wagon, comprising sides, ends and a bottom, the latter being formed of edge bars and a plurality of sections intermediate said edge bars of slightly lesser width than the space between said sides, the intermediate 105

110

- section being movable and the end sections fixed, top edge bars on said sides and ends, and parallel links connecting said movable sections to said edge bars, said links being 5 positioned and proportioned to permit the swinging of said section from the plane of the bottom into a plane adjacent to the top, with its upper face flush with the upper face of said top edge strips and its rear edge abutting against the rear end, the links in this 10 position of adjustment being inclined obliquely to the rear, for the purpose described.
5. A wagon, comprising sides, ends and a 15 bottom formed of fixed and movable sections, the movable section being intermediate fixed sections at opposite ends of the wagon, and parallel links arranged at opposite sides of the movable section and pivotally connected thereto, said links permitting 20

the swinging of said movable section from the plane of the bottom to a plane adjacent to the top and in the upper position of adjustment being inclined to the vertical, and an abutment engaged by the rear edge of the 25 movable section in its raised position.

6. A wagon, comprising sides, ends and a bottom, the latter being formed of edge bars and a plurality of sections intermediate said edge bars of slightly lesser width than the 30 space between said sides, and top edge bars on said sides and ends, the end section of the bottom being fixed and the intermediate section being adjustable from the plane of the end section to a position substantially 35 flush with the top edge strips, with its rear edge abutting against the rear end.

In testimony whereof I affix my signature.

ORAL CARMICHAEL.
